UNITED STATES PATENT OFFICE.

BROR F. BERGH, OF NEW YORK, N. Y., ASSIGNOR TO EDWARD J. N. STENT,
OF BAYONNE, NEW JERSEY.

ROCK-DRILLING MACHINE.

SPECIFICATION forming part of Letters Patent No. 308,947, dated December 9, 1884.

Application filed June 13, 1884. (No model.)

To all whom it may concern:

Be it known that I, BROR F. BERGH, a citizen of the United States, residing at the city of New York, county and State of New York, have invented a new and useful Improvement 5 in Rock-Drilling Machines, of which the following is a specification, reference being had to the drawings forming part of the same.

The class of machines to which my improvement is applied is that in which the movements of hand-drilling are imitated by the combination in a machine of a drill-holder, a hammer, mechanism for vibrating the hammer, and mechanism for feeding the hammer-bearing mechanism forward as the drilling 15 proceeds.

An example of the class of machines to which my improvement is applied is shown in the application of Henry F. Parsons and 20 myself, filed May 24, 1883, (Serial No. 36,024,) for Letters Patent.

The first part of my invention has for its object the communication of motion from the hand-levers to the hammer; and it consists in 25 locating upon the shaft operated by the hand-levers an arm to the extremity of which a double-ended pawl is pivoted at its center, and combining with this pawl a link attached to the hammer-arm at one end, and having its 30 other end so formed and located with reference to the pawl that for every forward movement of the hand-levers one end of the pawl engages with and disengages from a notch in the link, while for every backward movement 35 of the hand-levers the same operation is performed by the opposite end of the pawl, so that for each excursion of the hand-levers the hammer will be raised and dropped twice.

The second part of my invention has for its 40 object the connection of the spring with the hammer in such manner that less strain than heretofore will be brought upon the spring, and it will be less liable to be broken. It consists in connecting the hammer-arm with 45 the spring by interposing a stirrup, as hereinafter more fully explained.

The third part of my invention has for its 50 object the lifting and returning of the drill to the bottom of the bore-hole by a positive movement; and it consists in communicating an up-and-down movement to the drill-holder from

the hand-levers by a lever which receives a positive motion both upward and downward.

The fourth part of my invention has for its object so feeding the frame of the machine as 55 to have its position upon the guide-bars always locked when the feed is not required, but always unlocked just previous to the instant when any feed is required, so that the force of the hammer can never fall upon the 60 connections between the frame of the machine and the guide-rods. It consists in interposing between the drill-holder or plunger and the rack upon the guide-rod a carriage reciprocating in the frame, and provided with a tooth 65 to engage with the rack, and having its horizontal reciprocating movement governed by mechanism set in motion by a projection connected with the drill-holder or plunger, and its vertical reciprocating movement governed 70 by a rod or lifter receiving motion from the hand-levers.

My invention also consists in the details of construction.

I will now proceed to describe what I understand to be the best form of machine for embodying my invention, referring to the drawings.

Figure 1 is a side view of my machine with the guide-rods and the hand-levers removed. 80 Fig. 2 is a front view of my machine containing the sockets for the hand-levers, but not containing the guide-rods. Fig. 3 is a top view of my machine with the hammer-head and part of the hammer-arm removed. Fig. 85 4 is a cross-section through the line 4 4, Figs. 1 and 3. Fig. 5 shows a side view of the parts surrounding the plunger or drill-holder. Fig. 6 is a longitudinal section through the line 6 6, Fig. 5. Fig. 7 is a cross-section through 90 the line 7 7, Fig. 5. Fig. 8 is a cross-section through the line 8 8, Fig. 5. Fig. 9 is a side view of the plunger or drill-holder, with the parts immediately surrounding it in section. Fig. 10 is a front view of the mechanism connecting the hand-lever shaft with the hammer-arm. Fig. 11 is a side view of the same in section through the line 11, showing the position of the parts when the hammer is raised. Fig. 12 is the same, not in section, 100 showing the position of the parts when the hammer has fallen. Fig. 13 shows in detail

the form of the hole or recess in the carriage 6 for the pin 8.

First, as to the mechanism for creating and controlling the motions of the hammer: *a* is the shaft of the hand-lever, having its bearings in the frame of the machine. *b* is the frame of the machine. It consists at its forward end, as shown in cross-section at Fig. 7, of a vertical drill-holder or plunger on its forward side. Rearward from this barrel the frame extends in two parallel branches, which unite at their rear extremities at the point where the hammer-arm is pivoted. The operating mechanism is mainly contained between 15 and protected by these two branches of the frame, and upon the shaft *a* is fixed a vibrating arm, *c*, extending in the position shown in the drawings. This vibrating arm is forked toward its extremity, and within this fork is placed a double-ended pawl, *d*, which is secured within the fork by a pivot, *e*. The form of this pawl and the position in which it is secured with reference to the vibrating arm *c* and the shaft *a* is most clearly represented in 20 Figs. 11 and 12. Upon the hub of the vibrating arm *c*, near each extremity thereof, is mounted a disk, *f f'*. *g* is the hammer-arm, pivoted to the frame at *g'*. *h* is a link pivoted to the hammer-arm just forward of the 25 pivot *g'*, as shown in the drawings. This link *h* is forked at its forward end, so as to span the shaft *a*. The two branches *h' h''* of the forked end of the link are broadened toward their extremities, so as to bear upon the peripheries 30 of the disks *f f'*, and are thus kept always equidistant from the center of the shaft *a*. It will be seen that the forked link *h* is thus free to move forward and back upon the disks *f f'*, but is prevented by those disks from any lateral movement at its forward extremity. 35 Within each branch of the forked link *h*, and between the portions of the branch bearing upon the disks *f f'*, is cut a slot, *i i'*. Within each of these slots is introduced a stop or projecting flange, *j j'*. The length of the pawl *d* from the pivot *e* to its point, and also the curve of the pawl *d*, are regulated substantially as shown in Fig. 11—that is to say, they are so regulated that when one extremity of the 40 pawl engages with one of the stops *j* or *j'* the other extremity of the pawl will not be engaged with either of said stops, and the pawl is given play enough around its pivot *e* to alternately bring first one extremity and then 45 the other of the pawl into gear with the stops *j* or *j'*. In Fig. 1 the hammer is shown as down and the forked link *h* in its most forward position. The right-hand extremity of the pawl is shown in engagement with the stop *j* by dotted lines. By rotation of the shaft *a* in the direction of the arrow, the hammer is raised, the link *h* is pressed backward, and the pawl *d* is rotated to the position shown in Fig. 11, where the stop *j* is just at the point of dropping off the extremity of the pawl *d*. that it will not turn thereon and the other secured to the hand-lever, and these disks having upon their faces teeth to engage with each other, so as to prevent the disks turning upon one another. The teeth are held in engagement by a spiral spring located upon the shaft, which presses the disk attached to the hand-lever toward the disk attached to the shaft. The operator may force the disks apart against the spring and place the hand-lever in any position.

Second, as to the mechanism by which the drill is raised and lowered in the drill-hole: *o* is the drill-holder or plunger, to the bottom of which is secured the drill *o'*, and to the top of which is attached the striking-pin *o''*. This striking-pin is of the form shown, and is secured in place upon the top of the plunger *o* by a nut, *p*. The plunger *o* projects downward through the barrel formed by the frame of the machine *b*, but interposed between said barrel and the plunger is a sleeve, *q*. Below the sleeve *q* a collar, *r*, is interposed between the plunger *o* and the barrel *b*, and this collar *r* is pinned fast to the plunger. A stiff spiral spring, *s*, is placed around the plunger between the collar *r* and the sleeve *q*. The sleeve *q* is thus held downward by the nut *p* against the upward pressure of the spiral spring *s*, resting on the collar *r*. At its top the sleeve *q* is provided on opposite sides of the plunger with projecting pins *t t'*, and each pin is surrounded by a friction-roller. *u u'* are two levers of the form shown clearly in Fig. 1. The forward end of each of these levers is provided with a longitudinal slot so placed and formed as to fit the friction-rollers on the pins *t t'*. Toward its rear extremity each of the levers *u u'* is provided with a curved slot, *v v'*, and into each of these slots projects a pin, *w w'*, attached to the frame *b*, and provided at its outer extremity with a friction-roller interposed between it and the sides of the slots *v*. *x x'* are arms fixed with relation to the shaft *a* so as to turn with it, and each provided with an inward-projecting pin, *y y'*, which pass through the levers *u u'*. By the arrangement above described the motion of the shaft *a* in the direction of the arrow, Fig. 1, will throw the arms *x x'* forward, and their motion, being communicated through the pins *y y'*, will throw the levers *u u'* forward. The pins *t t'* and their friction-rollers advance from the forward end toward the rear of the slots in the levers *u u'*; but at the same time that these levers *u u'* are thrown forward the form of the slots *v v'* at their rear extremity will first cause that rear extremity to be lowered, and then raised again, thus vibrating the levers *u u'* about the pins *y y'* as centers and raising and lowering the forward ends of the levers simultaneously. When the shaft *a* is rotated in the opposite direction, the same action is repeated, and for each forward and each backward movement of the shaft *a* the forward ends of the levers *u u'* are raised and lowered simultaneously; but

since the levers *u u'* are at their forward ends engaged with the pins *t t'*, attached to the sleeve *q*, as already described, that sleeve will be raised and lowered in the same manner, and will in turn convey its upward and downward movements to the plunger *o*. Thus the distance that the plunger *o* is moved upward always corresponds exactly with the motion of the levers *u u'*, because the upper edge of the sleeve *q* rests directly against the lower edge of the nut *p*. On the other hand, provision is made, by interposing a stiff spiral spring, *s*, between the sleeve *q* and the collar *r*, so that the downward stroke which the plunger *o* receives from the levers *u u'* may be very slightly elastic. This elasticity is provided for the following reason: The feed of the frame of the machine is intermittent, and each time it feeds it moves forward about one-quarter inch. Between the intervals of feed the drill advances into the rock at each blow of the hammer, and thus the plunger or drill-holder will, while resting at the bottom of the bore-hole, at times be farther forward in the barrel of the frame than at others. The reciprocation of the plunger or drill-holder in the barrel of the frame must therefore be greater at some times than at others, while the reciprocation of the forward ends of the levers *u* is always the same. To provide for this difference, and at the same time to insure that the drill shall always be returned to the bottom of the bore-hole, is the object of the spring *s*, which will be compressed when the downward motion of the forward ends of the levers *u u'* is greater than the downward motion of the plunger or drill-holder *o*.

Third, as to the mechanism for turning the drill: Upon the periphery of the nut *p* are placed ratchet-teeth *p'*. On the top of the lever *u* is pivoted a pushing-pawl, *z*, and on the top of the lever *u'* is pivoted a pulling-pawl, *z'*. These two pawls are pivoted at the extremities opposite to their teeth, and their toothed ends are held together by a spiral spring, *2*, as clearly shown in Fig. 3. It will be seen that by each movement of the levers *u u'* backward the pawl *z'* will engage with the ratchet and rotate the drill-holder or plunger in the direction of the arrow, Fig. 3, and that with each forward movement of the levers *u u'* the pawl *z* will engage with the ratchet and move the drill-holder in the same direction. Thus the drill-holder will be rotated the distance between the teeth of the ratchet for every backward and every forward movement of the levers *u u'*. The parts already described for lifting the drill and the relationship between the teeth of these pawls and ratchet are so timed that the drill will be lifted from the bottom of the drill-holder before it is turned. Thus breakage and wear of the edge of the drill which would result from turning it before lifting it are prevented.

Fourth, as to the mechanism for feeding the machine forward so as to keep pace with the advance of the drill into the rock: The frame

of the machine *b* is provided on either side, nearly opposite the barrel, with suitable recesses at 3 3 3 3, to fit upon the guide-rods 4 4, which are arranged similarly to those shown in the application of Henry F. Parsons and myself, before referred to. Upon one of these guide-rods, as the one located at the left-hand side of the drill-holder, is secured a rack, 5. 6 is a carriage, which is so secured that when not locked it may reciprocate either vertically or horizontally, it being held in position by slotted connections with the rod 7 and pin 11. The reciprocating carriage 6 is provided with a tooth, which takes into the rack 5. The sleeve *q*, at its upper end, is provided with a backwardly-projecting lug, into which is screwed a downwardly-extending rod, 7. This rod projects downwardly through the frame *b*, in which it has its bearings, as shown in Fig. 6, but in which it is free to reciprocate up and down. This rod 7 passes through a horizontal slot in the carriage 6, as indicated in Fig. 8, and just below the point where it is encircled by the carriage the rod is provided with a shoulder, as shown in Figs. 6 and 1. This shoulder is so located that when the carriage is in the position shown in Fig. 6 the rod 7, which is reciprocated up and down with the sleeve *q*, may move without affecting the carriage 6, but so that whenever said carriage falls below the position shown in Fig. 6 it will be struck by the shoulder referred to on the upward stroke of the rod 7. The carriage 6 has a downward prolongation, as shown in Fig. 6, and through this prolongation is cut a hole of the form shown in Figs. 13 and 6. This hole is made up of two portions—first, a slotted portion extending all the way through the carriage 6 in a horizontal direction, and, second, an enlarged circular portion which extends a part of the way through from the rear of the said carriage. Into this hole is fitted a pin, 8, which is also made up of two portions—first, a circular portion which is just long enough to extend through the slotted hole in the carriage, and, second, an enlarged circular portion which is of the same size as the enlarged circular hole in the carriage, and which projects backward from the carriage through a lug, 9, on the frame of the machine and beyond the said lug, and which bears at its rear end against the spring 10, secured to the frame of the machine, as shown in the various figures. When the carriage 6 is in its highest position, as shown in Fig. 6, the enlarged part of this pin fits into the enlargement of the hole in the carriage 6, already referred to, and since this enlargement of the hole is circular and not slotted, the carriage can move neither upward nor downward upon the pin 8, but is secured by that pin, and locked firmly to the frame of the machine, through which, as above stated, the pin passes. When, however, the pin is forced backward against the action of the spring 10 such a distance that the enlarged portion of the pin is thrown out of the hole in the carriage 6, then

the carriage is free to move up and down to the extent provided for by the slotted form of the smaller portion of the hole in the carriage 6. The lower extension of the carriage 6, after passing by the point where it is perforated by the pin 8, extends downward and receives in a vertical slot near its lower extremity the pin 11, and below that pin is provided a spiral spring, 12, which tends to press the carriage 6 downwardly. 13 is a lever pivoted on the pin 11 and provided with three arms, 14, 15, and 16. The arm 15 projects horizontally in such position below the collar *r* on the plunger or drill-holder *o* that whenever said plunger or drill-holder has advanced to a point where it is desirable for the frame of the machine to be fed forward the further advance of said plunger or drill-holder will cause the collar *r* to press the arm 15 downwardly. The arm 14 extends upwardly along the face of the carriage 6 and opposite to the end of the pin 8, projecting through said carriage, as shown in Fig. 6. When the carriage 6 is locked to the frame by the pin 8, as already described, the arm 14 will rest against the end of the pin 8; but when the collar *r* on the plunger has advanced, as already described, so far as to press the arm 15 downward, the arm 14 will thereby be moved so as to press the pin 8 inward against the action of the spring 10 until the enlarged portion of said pin is entirely clear of the hole in the carriage 6, as indicated in dotted lines in Fig. 2; but the parts are so adjusted that the motion of the arms 15 and 14 do not stop until the arm 14 has not only pressed the pin 8 backward, as described, but also until the arm 14 has pressed the carriage 6 back into the position shown in Fig. 2, where the tooth of the carriage 6 is disengaged from the teeth of the rack 5. The spring 12 now comes into play and forces the carriage 6 downward the distance between two teeth of the rack 5, and so that the tooth on the carriage is in the proper position to engage between the two teeth of the rack next below the two with which it had been previously engaged, or in the position shown in Fig. 2. The plunger or drill-holder is now lifted, and with it the collar *r*, so as to release the arm 15 and permit the spring 10, acting through the medium of the pin 8, to force the carriage 6 forward again until the tooth upon it is brought into gear with the rack. As yet, however, the carriage 6 is not locked to the frame, because it is too low down with reference to the pin for the enlargement of the pin to enter the enlargement of the hole in the carriage. As, however, the drill is lifted the shoulder on the rod 7 comes in contact with the carriage 6. Now, the carriage is prevented from moving upward by the engagement of its tooth with the rack, and consequently the frame of the machine is slid downward on the guide-rods 4 a distance corresponding with the distance between the teeth of the rack 5. This changes the relative position of the carriage 6 and the other

parts from that shown in Fig. 2 to that shown in Fig. 6, and the enlarged part of the pin 8 is then pressed forward by spring 10 into the enlargement of the hole in carriage 6, and the 5 parts are firmly locked again, and continue so until the drill has advanced far enough to make another feed necessary, when the same operations are repeated. The collar *r* is so placed on the plunger that it will strike the arm 15 10 and force the tooth on carriage 6 out of engagement with the rack before the hammer has driven the plunger far enough for the force of the hammer to strike the frame. Thus the connection between the frame and the rack 5 15 can never be strained or broken by any strain from the blow of the hammer. The collar *r* should always be so placed on the plunger that the feed will take place sufficiently often to always place the point of the drill on the bottom of the bore-hole a little before the forward ends of the levers *u u'* have completed 20 their downward strokes, so that the blow of the hammer shall never be communicated to the levers *u u'*. 25 Fifth, as to mechanism whereby the operator may unlock the frame of the machine from the rack 5 to move the frame back on the guides or otherwise adjust the machine: The arm 16 of the lever 13 rests on a pin, 17, which may 30 be turned by the thumb-handle 18. A recess is cut on one side of the pin 17, which may be brought opposite the arm 16 by turning the pin. When the machine is working, the recess is opposite the arm 16, and in that condition the pin 17 does not affect the described 35 operation of the lever 13. When, however, the pin 17 is turned, it raises the arm 16, and, throwing the arm 14 forward, forces the pin 8 backward and disengages the tooth on carriage 6 from the rack. This the operator can 40 do at any time by turning the thumb-handle 18, and he can then move the frame in any way he pleases on the guide-rods 4. When in the operation already described the tooth 45 of the carriage 6 is disengaged from the rack 5, it is necessary that there be something to prevent the frame from dropping on the guides 4 of its own weight. This is effected by a clamping device on the pin 17, which presses 50 against the guide-rod 4 to produce sufficient friction to hold the frame of the machine up against its own weight. 20 is a spring-plate attached to the frame *b*, and having its free end extend out opposite to the guide-rod 4. 55 A friction-block, 21, which may be faced with leather, is interposed between the free end of the spring-plate 20 and the guide-rod 4. The pin or spindle 17 projects through a hole in the spring-plate 20, to which it is secured. 60 Between the head 22 of the pin 17 and the adjacent face of the frame *b* are formed cam or V shaped surfaces, so that when the pin or spindle 17 is turned in the position shown in the drawings the pin will be retracted to the extent provided for by the cam-surfaces, so as 65 to press the spring-plate 20 and create friction between the block 21 and the guide-rod 4.

This is the position of the pin 17 when the described automatic feeding devices are in operation, and it will thus be seen that the frame 70 of the machine will be held up against its own weight, and only be fed forward by the mechanism provided for that purpose. When, however, the handle 18 is turned so as to throw the carriage 6 out of gear with the rack 5, the 75 form of the cam-surfaces is such as to permit the spring-plate 20 to draw the pin 17 inward and break the friction-connection between the friction-block 21 and the guide-rod, so that the frame moves freely upon the guide-rod. 80

I do not wish to be understood that all of the parts or combinations described are necessary, or that I intend to limit myself to combinations containing them all.

I am aware that parts of my invention, 85 which I have described may be used without others, and that in my description of each part I have described devices which in some cases might be omitted and in many cases might be replaced by other devices for the 90 same purpose without departing from the essential principles of my invention.

I am aware that the striking-pin and the device for securing the same are old, as claimed in my previous application No. 96,024, and I 95 do not herein claim anything claimed therein.

I claim—

1. The combination, with a drill-holder, of a hammer for actuating said drill-holder, a bifurcated link connected with said hammer, 100 a hand-lever, and a double-ended pawl actuated by the hand-lever for imparting motion to the link, substantially as described.

2. The combination, with a drill-holder, of a hammer for actuating said drill-holder, a bifurcated link connected with said hammer, a hand-lever, a double-ended pawl actuated by the hand-lever for imparting motion to the link, a lever or levers connected with the hand-lever, whereby a positive up-and-down motion is imparted to the drill, a ratchet on the drill-holder, and a pawl or pawls actuated by the said last-mentioned lever or levers for imparting a rotary motion to the drill, substantially as described. 110

3. In combination, the drill-holder, the collar rigidly secured thereto, the sleeve, the spring interposed between the collar and the sleeve, the drill-lifting lever or levers provided with slotted connections with the sleeve 120 and frame, the drill-turning pawl or pawls, the said drill-lifting and drill-turning devices being operated by one set of levers, substantially as described.

4. The combination, with a drill-holder, of 125 a nut bearing a ratchet thereon, a lever or levers bearing a pawl or pawls for engaging with said ratchet, a sleeve fitting loosely about said drill-holder and having a positive connection with said lever or levers, a collar rigidly affixed to said drill-holder, a spring between the sleeve and the collar, and a hand-lever for imparting motion to said lever or levers, the whole being so arranged and combined that 130

the lever or levers may be operated to raise and lower the drill-holder and to rotate the same, substantially as described.

5. The combination, with a sliding frame which carries the drill and its operating mechanism, of a hammer, a drill-holder, a collar rigidly affixed thereto, a lever having one arm extended in the line of movement of said collar, a carriage having a lateral movement in the sliding frame, and a fixed rack with which said carriage is normally engaged, the whole being so arranged and combined that the forward movement of the drill-holder will operate the lever to cause the carriage to become disengaged from said rack, substantially as described.

6. The combination, with the sliding frame which carries the drill and its operating mechanism, of a hammer, a drill-holder, a collar on said drill-holder, a lever having one arm extended in line with the movement of said collar, a carriage having a lateral movement in the frame, a fixed rack with which said carriage is normally engaged, a pin engaging said carriage, and a spring for holding said carriage in engagement with the rack, all being arranged substantially as described, whereby said pin may be moved out of engagement with the carriage and the carriage may be moved out of engagement with the rack, substantially as described.

7. The combination, with the sliding frame which carries the drill and its operating mechanism, of a fixed rack with which engages a carriage on said sliding frame, a rod, 7, connected with the reciprocating drill-holder and bearing a stop to engage with said carriage, and mechanism, substantially as described, for imparting a vertical and lateral

movement to said carriage relatively to the 40 sliding frame, all substantially as described.

8. The combination, with a sliding frame which carries the drill and its operating mechanism, of a fixed rack, a carriage on said frame engaging normally with said rack, a 45 lever adapted to move said carriage out of engagement with said rack, a cam on the sliding frame bearing against said lever, and means, substantially as described, for operating said cam, substantially as described. 50

9. The combination, with the sliding frame which carries the drill and its operating mechanism, of a hammer, a drill-holder, a collar on said drill-holder, a carriage having a lateral movement in the frame, a fixed rack 55 with which said carriage is normally in engagement, a lever actuated by the drill-holder for imparting motion to the carriage in a backward direction, a spring for imparting motion to said carriage in a downward direction, and 60 another spring for imparting motion to said carriage in a forward direction, substantially as described.

10. The combination, with the frame *b*, which carries the drill and its operating mechanism, 65 of the guide-rods 4, the friction-blocks 21, attached to the spring-plate 20, which is secured to the frame *b*, the pin 17, bearing against the spring-plate, and the thumb-piece 18 and cam 22 on said pin, the mechanism being adapted 70 to force the friction-block into contact with said guide-rods to support the frame, substantially as described.
